UNITED STATES PATENT OFFICE.

EDGAR W. INGRAM, OF WICHITA, KANSAS.

CAP.

Application filed August 2, 1926. Serial No. 126,678.

This invention relates to the general class of headgear but more particularly to caps such as are used by kitchen attendants, operatives in restaurants and similar places.

5 It is practically a universal law that any one handling food in a public institution must wear some sort of a head covering so cotton caps are generally used. While they serve the purpose satisfactorily they are comparatively expensive as to first cost and the laundering expense is quite an "overhead" item. They frequently wear out and besides they are not adapted to fit different sized heads.

I have found that it is perfectly feasible to 15 provide a cap formed from a single blank susceptible of expansibility so that the cap can be made larger in the event that it is too small and that if desired the blank may consist of paper, crêpe paper being an admirable 20 material for this purpose. The blank can be so folded that a moisture band commonly known as a "sweat band" will be formed within the crown to take up the moisture incident to perspiration. When the cap is formed 25 from a paper blank the completed article will cost considerably less than the actual cost of laundering the fabric cap so the necessity for the expense of a fabric cap will be entirely eliminated.

30 There are other novel features of my invention which will be specifically described hereinafter, reference being had to the accompanying drawings in which:

Fig. 1 is a perspective view of the blank 35 showing an edge fold for reinforcing the edge of the opening in the center of the crown and the transverse folds for providing for the extensibility of the completed cap.

Fig. 2 is a perspective view showing two 40 additional end folds with part of the blank folded over longitudinally.

Fig. 3 is a like view showing the additional 45 step of folding the blank with a top fold.

Fig. 4 is a like view showing the sweat band 50 fold.

Fig. 5 is a perspective view showing the two ends of the blank interlocked with the sweat band fold unfolded, so that the ends of the blank can be connected and,

55 Fig. 6 is a perspective view of the completed cap, parts being broken away to show the relative positions of the plies.

A single rectangular sheet 1 is provided with transverse extensible folds 2 and a side 55 edge lapped over fold 3 as shown in Fig. 1.

Then the portion 4 is folded over upon the blank at fold line 5, the ends of the blank are then folded over to provide interlocking folds 6 and 7, one being beneath the blank and the other on top as shown in Fig. 2, the 60 part 4 lying upon the part 8 between the fold lines 5 and 9 so that there will be two thicknesses to provide for the brim. The part 10 which is the crown portion is now folded forwardly on top of the parts 4 and 8 along 65 the fold line 9 as shown in Fig. 3. The blank is then folded at the fold lines 11 and 12 to form the double thicknesses 13 and 14 which constitutes the sweat band 15 as shown in Fig. 4. The blank is now ready for assembly. 70 In order to assemble it the blank is unfolded at the fold lines 9, 11 and 12 and the interlocking folds 6 and 7 are brought together and interlocked as shown in Fig. 5. At this time the part 4 is inside the open ended cylinder formed by interlocking the edges 6 and 7 as shown in Fig. 5. Then the part 10 which is wider than the parts 4 and 8 is brought 75 up inside the cylinder and the sweat band is folded back inside the brim and crown as shown in Fig. 6. The edge 3 is gathered in to form a central hole 16 in the crown, the folded in portions of the edge 3 being pasted or otherwise secured together to make the completed crown. The cap is now ready for 80 use provided with a double walled brim 17, a sweat band 15 and a single walled crown 18.

If it is desired to make the cap larger one or more of the folds 2 can be pulled apart as 85 shown in Fig. 6, by gripping the brim on respective sides of the folds and pulling the folds apart by the thumb and forefinger of each hand as indicated at 19 and 20. If the cap is made of crepe paper the sweat band 15 will absorb the moisture due to perspiration. So it will be seen that an inexpensive 90 cap can be made of a single blank of paper having all of the advantages of a fabric cap without any of its disadvantages.

What I claim and desire to secure by Letters Patent is:—

1. A blank for headgear consisting of flexible material having transverse pleats and longitudinal fold lines passing through the 100 pleats certain of the pleats being embraced between the plies of said folds whereby when the headgear is complete, the pleats will be held in frictional contact by the folds, one of the 105 folded over portions constituting the crown and another folded over portion constituting 110

the brim, the edge of the brim being folded under to provide a sweat band.

2. A blank for headgear consisting of flexible material having transverse pleats and longitudinal fold lines passing through the pleats certain of the pleats being embraced between the plies of said folds whereby when the headgear is complete, the pleats will be

held in frictional contact by the folds, one of the folded over portions constituting the crown and another folded over portion constituting the brim, the base of the crown and the brim having a folded under portion to provide a sweat band.

In testimony whereof I affix my signature.

EDGAR W. INGRAM.
